BELT BUCKLE

Application filed July 10, 1930, Serial No. 467,079, and in Switzerland July 16, 1929.

This invention relates to buckles for belts and the like, comprising two pivotal coupling members adapted to be turned on one another and one of them being adjustably connected with the one end of the belt.

Belt buckles of this type were heretofore proposed to be applied to bracelets and the like. When such buckles were used for instance, on shoe straps they were not satisfactory as they did not permit of a ready, convenient and precise tensioning and detaching of the strap and at the same time of effectively preventing an unintentional disengagement of the buckle on bumping the same or getting entangled therewith and so on. Therefore, none of the known buckles could successfully be introduced on the market as buckles for shoe straps. The known buckles of this type did not enable the belt to be exactly adjusted to any circumference to be embraced by the latter only an adjustment of the belt in steps being possible or the locking of the buckle was to be effected by means of a not easily accessible snap-bolt to be pressed by the finger nails which for certain purposes was not handy. Other known devices of this kind provided for the free belt end to be entered in a clasp, but so as to be retained therein in the locking position of the same only and during the locking operation could freely shift relatively to the clasp so that when the device was applied to shoes a suitable tensioning of the straps was scarcely possible. Moreover, the clamping of the strap required special manipulations and the working surfaces of the clasp were subjected to considerable wear by the strap. The latter disadvantage was still more noticeable when the strap dried out and consequently its cross-section was reduced, thus rendering a safe clamping impossible.

The object of the invention is to eliminate the above said disadvantages, in that according to the invention the free end of the one coupling member provides a cross-bar for a

clasp frame pivotally connected thereto, such wise, that the belt inserted in the clasp frame, during the displacement of the said member into its locking position in the buckle, is at the same time tensioned and clampingly secured to the clasp frame. Suitably the arrangement is such that the coupling member connected with the clasp frame is formed with an extension which during the locking movement of the buckle enters in the clasp frame and which is provided with a groove in which in the locking position of the buckle a hook shaped extension on the other coupling member is forced to engage.

Owing to this arrangement the belt or strap, during the locking of the buckle, is automatically adapted to the foot i. e. to the circumference of the body to be embraced and as the coupling is completely covered by the clasp no undesired disengagement of the buckle by bumping or getting entangled therewith is possible whilst on the other hand for opening the buckle a mere lifting of the clasp frame is required. Besides, the extension has imparted a high spring action thereto and is provided with rounded-off catching surfaces, thus avoiding the safety of the locking engagement to be diminished due to the spring action relaxing or the catching surfaces being worn.

In the drawings several embodiments of the invention are illustrated by way of example wherein

Figs. 1 and 2 show in longitudinal section and in top view respectively the buckle in open position;

Fig. 3 is a longitudinal section showing the buckle in closed position;

Fig. 4 is an elevational view of a belt provided with the buckle, on a smaller scale, and

Fig. 5 is a longitudinal section of a second embodiment of the invention.

The pivot joint 1 is connected to a coupling member 2 which is fastened to the one end A of a belt R and which protrudes the said

end by an extension 3 bent up from the member at right angles and thickened at its extreme end. The other coupling member 4 is formed at its free end with an enlarged 5 and thicker extension 5 the end surface of which corresponds exactly to the inner catching surface of the extension 3 of the other coupling member and which surrounds the latter extension in the locking position (Fig. 10 3) of the buckle, the said end surface being provided with a groove into which the bead on the extension 3 is adapted to engage. The free end of the coupling member 4 is further provided with a pivot pin 6 on which a clasp 15 frame 7 is mounted through which the other belt end B is passed, and the pin 6 is positioned exteriorly of the plane of the clasp frame end eccentrically with respect to the extension 5, suchwise, that in the position of 20 the parts shown in Fig. 1 wherein the clasp frame is transversely disposed to the coupling member 4 the belt engages the clasp with clearness and is adapted to be readily pulled through the latter for adjustment, whereas in the position of the clasp when it 25 is turned to extend parallel to the said coupling member the extension 5 enters in the clasp frame and clamps the belt thereto to be securely held, as shown in Fig. 3.

30 The coupling member 2 is either riveted to the end A of the belt or sewed thereon and positively prevented by the extension 3 from disengagement therewith.

In the open condition of the buckle shown 35 in the Figs. 1 and 2 the belt end B is adjusted in the clasp to the required extent. Thereupon, the clasp frame is gripped and the coupling member 4 turned to the left, whereupon the buckle is completely locked by applying an increased pressure on the clasp, 40 whereby the extension 3 is first pushed aside to subsequently be forced into the groove of the extension 3 by spring action. Thus, the buckle is securely locked as the tension in the part B of the belt acts approximately in the 45 direction of the coupling member 4 on the pivot 1 above the axis of the latter and consequently is not enabled to open the lock the latter being secured by spring action of 50 the extension 3, so that also the end of the belt is prevented from shifting in the clasp.

The buckle is opened by merely lifting the clasp frame, whereby the coupling member 4 is automatically turned to the right and the 55 belt is widened corresponding to an increased length thereof which is equal to the double length of the coupling member 4, so as to be adapted to be readily stripped off the body which it embraces.

60 In the constructional form of the buckle, as shown in Fig. 5, the coupling member 12 is inserted between the two halves of the end A₁ of the belt and secured thereon by means of a rivet 18. The rivet 18 has an upper 65 head 19 which in the locking position of the

buckle projects through an opening 20 in the coupling member 14. The front end 15 of the coupling member 14 forms a cross-bar for the clasp and is provided with lateral ears for the reception of the pivot pin 16. For locking the buckle the head 19 must be pushed through the opening 20 in which position the head holds the coupling member 14 the end portion 15 of which securely clamps the belt end B₁ to the clasp frame in the locking 75 position of the buckle.

I claim,

1. In a belt buckle of the type described, in combination, two coupling members pivotally connected to each other, a clasp frame pivotally mounted on the outer end of its correlated coupling member, means on the outer end of the coupling member correlated to the said clasp frame providing a cross-bar for the said frame for clamping the free belt portion 80 to the frame when the two coupling members approach each other, and locking means on the outer end of each coupling member for securing the coupling members in their closed position.

2. In a belt buckle of the type described, in combination, two coupling members pivotally connected to each other, a clasp frame pivotally mounted on the outer end of its correlated coupling member, a projection on the outer end of the coupling member correlated to the said clasp frame entering the said frame for clamping the free belt portion to the frame when the two coupling members are closed on 85 one another, a groove in the said projection, and a hook shaped extension on the outer end of the other coupling member being forced into the said groove when the two coupling members approach each other so as to secure the coupling members in their closed position.

3. In a belt buckle of the type described, in combination two coupling members pivotally connected to each other, a clasp frame, a pivot pin for the said clasp frame on the outer end of one of the said coupling members, a projection on the outer end of the coupling member correlated to the said clasp frame entering the said frame for clamping the free belt portion to the frame when the two coupling members are closed on one another, the said pivot pin being disposed exteriorly of the plane of the said clasp frame and eccentrically to the said projection so that the free belt portion is released in a transverse position of the said frame in respect to its correlated coupling member and clamped to the frame in a position of the latter parallel with the said member, a groove in the said projection, and a hook shaped extension on the outer end of the other coupling member being forced into the said groove when the two coupling members approach each other, so as to secure the coupling members in their closed position.

4. In a belt buckle of the type described, in combination, two coupling members pivotally

connected to each other, a clasp frame pivotally mounted on the outer end of its correlated coupling member, means provided on the coupling member correlated to said clasp frame for clamping the free belt portion to the frame in every position of the belt relatively to the latter when the two coupling members approach each other, and locking means arranged between the two coupling members for securing said members in their closed position.

10 In testimony whereof I have signed my name to this specification.
